UNITED STATES PATENT OFFICE

2,101,018

CONVEYER DRIVING MECHANISM

Charles N. Bebinger, New Philadelphia, Ohio, assignor to La-Del Conveyor & Mfg. Co., New Philadelphia, Ohio, a corporation of Ohio

Application March 3, 1937, Serial No. 128,822

12 Claims. (Cl. 198—218)

The invention relates generally to driving mechanism for shaking conveyors, and more particularly to a spring driving mechanism which is quickly and easily reversible.

5 Prior constructions have provided a spring drive for imparting a reciprocating motion to a conveyor for conveying material in one direction, and such a construction is disclosed in my prior Patent No. 2,049,346, issued July 28, 1936, 10 and entitled Spring drive for shaking conveyors.

It is desirable, particularly where the conveyor is used in underground work, to be able to reverse the stroke of the driving mechanism to reciprocate the conveyor for conveying material 15 in the opposite direction, and none of the prior constructions, of which I am aware, provides a spring drive which is intended to be or can easily be reversed.

Where a shaking conveyor is utilized for conveying coal out of a mine, for example, by reversing the drive the conveyor can be utilized to transport supplies used in mining into the mine.

Accordingly, the principal object of the present invention is to provide a reversible spring 25 driving mechanism for a shaking conveyor.

Another object is to provide a spring driving mechanism which can be easily reversed in a minimum amount of time.

A further object is to provide a reversible 30 spring drive constructed as a unit, and adapted at either end for detachable connection with the driving crank and connected with a reciprocable support secured to the conveyor.

A still further object is to provide an improved 35 reversible spring driving mechanism which is of simple and rugged construction, and which is adapted to produce an efficient conveying action in either direction.

These and other objects are attained by the 40 parts, improvements, combinations and arrangements comprising the present invention which is hereinafter disclosed, described and claimed.

In general terms the invention may be stated 45 as including a spring drive for imparting reciprocating conveying motion swiveled on a motion-transmitting member connected to a conveyor, and one end of the spring drive being detachably connected to a driving crank, whereby the drive 50 can be rotated on the motion-transmitting member for connecting the opposite end of the drive to the crank to reverse the conveying motion.

Referring to the drawings forming part hereof—

Figure 1 is a side elevation of the improved 55 reversible drive operatively connected to a shaking

conveyor for imparting reciprocating conveying motion thereto;

Fig. 2 is an enlarged fragmentary section as on line 2—2, Fig. 1;

Fig. 3 is a fragmentary section as on line 3—3, 5 Fig. 2;

Fig. 4 is an enlarged fragmentary longitudinal section of the improved spring drive unit;

Fig. 5 is a transverse section taken on line 5—5, Fig. 4; and 10

Fig. 6 is a transverse section as on line 6—6, Fig. 4.

Similar numerals refer to similar parts throughout the drawings.

The shaking conveyor includes troughs connected end to end for carrying material, two of said troughs being represented at 10 and 11 in the drawings. The motive means for driving the conveyor is preferably an electric motor (not shown) which is connected in a usual manner 20 through a gear box indicated at 12 to a flanged member 13 on which is eccentrically mounted a driving crank member 14. The driving crank 14 imparts reciprocating motion to the spring driving mechanism of the conveyor, and may be 25 termed a reciprocating driving member.

The gear box 12 may be mounted on a suitable base plate 15 extending under the conveyor, and a roller 16 for supporting the conveyor trough 10 may be mounted in a supporting 30 bracket 17 secured on the base plate 15.

A reciprocable support indicated generally at 18 is provided for the conveyor preferably at the joint between troughs 10 and 11. The support 18 preferably includes a joint member 19 having 35 an upright flange 20 for fitting between the adjoining ends of troughs 10 and 11 and secured thereto by bolts 21 passing through the flange 20 and eye bars 22 secured on the ends of the troughs. The joint member 19 is also provided 40 with arms 23 extending longitudinally under the troughs for abutting the under sides thereof.

A transverse roller shaft 24 is mounted in depending portions of the joint member 19 and has flanged rollers 25 rotatably mounted on its ends by means of suitable anti-friction bearings, for rolling on track rods 26 located at each side of the conveyor. The track rods 26 may be secured as is shown to angles 27 supported on a suitable base 28. 45

The reciprocable support 18 accordingly provides anti-friction means for movably supporting the conveyor as it is reciprocated by the driving mechanism.

The improved reversible spring driving mech- 50 55

anism preferably includes a guide rod 30, one end of which is preferably screwed into the driving crank member 14, and the other end is slidably mounted in a connecting member 31 which is 5 pivotally mounted on the transverse roller shaft 24. The connecting member 31 is preferably provided with an upright flange 32 positioned in a slot 33 in the joint member 19, and the flange 32 is pivotally mounted on the roller shaft 24 by 10 means of a self-aligning bearing indicated at 35.

Thus the connecting member 31 is pivotally connected to the reciprocable support 18 for relative movement about a horizontal axis.

A driving sleeve or motion-transmitting member 36 is slidably mounted on the guide rod 30 and is secured at one end to the connecting member 31, as best shown in Fig. 3. Preferably the end of sleeve 36 is received in an enlarged bore 37 in the connecting member 31 and is secured to the 15 connecting member as by welding indicated at 38.

The reversible spring drive unit indicated generally at 40 is swiveled intermediate its ends on the driving sleeve 36, and as best shown in Figs. 4 and 5, the cross head 41 of the unit has an annular journal member 42 mounted therein, and a collar member 43 surrounds and is secured as by welding to the sleeve 36 and has a journal portion 44 fitting within the annular journal member 42, for swiveling the unit on the driving sleeve member 36. Bolts 45 are provided for securing the member 43 to the journal member 42, there being suitable passages indicated at 46 through the collar member 43 and the sleeve member 36 providing for lubrication, and access to said passages is provided by a plug 47 screwed into the collar member 43.

As shown, the annular journal member 42 is provided at its lower end with an annular flange 48 which is held in abutment with a shoulder formed in the upper portion of the cross head member 41 by the bolts 45.

A lubricant compartment 49 is formed in the lower portion of the cross head, and communicates with longitudinally extending bores formed 45 in tubular projections 50 at opposite ends of the cross head. Cover plates 51 are detachably secured to opposite sides of the cross head by screws 52 for giving access to the compartment 49.

A rod 54 is slidably mounted in the bores of the 50 tubular projections 50 and extends through the lubricant compartment 49. A thrust member 55 is screwed on one projecting end of the rod 54 and has a tubular portion 56 extending toward the cross head, and a thrust member 57 is screwed 55 on the other projecting end of the rod and has a tubular portion 58 extending toward the cross head.

A relatively strong compression spring 59 is interposed between the cross head member 41 and 60 the thrust member 55, and the tubular projection 50 of the cross head and the tubular portion 56 of thrust member 55 form centering means for said spring 59.

Similarly, a relatively weak compression spring 65 60 is interposed between the cross head 41 and the thrust member 57, and the tubular projection 50 of the cross head and tubular portion 58 of thrust member 57 form centering means for said spring 60.

70 Each of the thrust members 55 and 57 are preferably provided with split lower portions 61, as best shown in Fig. 6, and clamping screws 62 are provided for drawing the portions 61 together and clamping them around the threaded ends of 75 the rod 54. Each of the thrust members 55 and

57 are also provided with latch pin apertures 63 to adapt them for selective detachable connection with crank 14 as will be described.

A latch 64 is pivotally mounted on the crank member 14 as at 65, and the latch 64 preferably has an inverted U-shaped portion 66 which straddles the guide rod 30. The U-shaped portion 66 of the latch preferably has aligned latch pin apertures 67 (Fig. 6) for registering with the latch pin aperture 63 of either of the thrust members 55 or 57, so that a latch pin 68 may be inserted through the apertures 67 and 63 to selectively and detachably connect the driving crank with a thrust member at either end of the spring drive unit 40.

As shown in the drawings the driving crank is connected to the thrust member 55 by means of the latch 64 and latch pin 68 and the conveyer is accordingly adapted to convey material to the right, as viewed in Fig. 1 and represented by the 20 arrow. In operating the conveyer, it is customary to initially adjust the thrust member 57 by loosening the bolt 62 and taking up the thrust member on the rod 54 approximately 2" to place the springs 60 and 59 under compression, although the amount of adjustment may be varied to obtain the most effective conveying stroke for a given conveyer load.

In Fig. 1 both springs are shown extended to their normal free length, but in operating the 30 conveyer the thrust member 57 is first adjusted to place the springs under compression, in the manner above described. Since the spring 60 is much weaker than spring 59, spring 60 will be compressed by a greater amount than spring 59, so that after adjustment the distance from the cross head to thrust member 57 exceeds the distance from the cross head to member 55 by an amount substantially equal to the throw or stroke 35 of crank member 14.

As the crank 14 moves to the left as viewed in Fig. 1 the stroke is transmitted through latch 64, thrust member 55, strong compression spring 59, cross head 41, sleeve member 36, and support 19 to the conveyer. On the return stroke of 45 the crank the motion is transmitted through thrust member 57 and weak compression spring 60 to the cross head 41, sleeve 36 and thence to the conveyer.

Due to the unequal strength of springs 59 and 60 movement of the conveyer to the left will be relatively sudden and rapid so as to slide under material on the conveyer, and movement on the return stroke in the opposite direction will be relatively slow and gradual because of the weaker spring 60 so as to carry material forward in the direction of the arrow. Thus the springs 59 and 60 impart a differential stroke to the conveyer to give it a conveying action.

If it is desired to convey material in the opposite direction, that is, to the left as viewed in Fig. 1, it is only necessary to remove pin 68 from engagement with thrust member 55, lift latch 64 and swing or swivel the spring drive unit 40 horizontally about the substantially vertical axis 35 of the journal 42, and then insert the latch pin 68 in the aperture 63 of thrust member 57 for connecting the opposite end of the spring drive unit to the crank 14.

This operation is easily accomplished by positioning the crank 14 at its extreme left position, and then pulling out the latch pin 68 and reversing the spring drive 40 to bring the thrust member 57 in position for connection with the latch. The crank is then moved to the right approach- 75

ing its extreme position in that direction until the latch pin hole 63 of thrust member 57 registers with the latch pin hole 67 of the latch, whereupon the latch pin is again inserted to connect the thrust member 57 with the crank, and the conveying action will be in the opposite direction.

If for example, a shaking conveyer embodying the improved driving mechanism is being utilized for conveying coal out of a mine, the driving mechanism can be quickly and easily reversed to utilize the conveyer for transporting supplies into the mine.

The improved driving mechanism includes a reversible spring drive unit which is connected to a reciprocable support secured to the conveyer, and adapted at either end for detachable connection with the driving crank.

The improved reversible driving mechanism is simple and rugged in construction, and is easily adjustable for producing the most efficient conveying action in either direction for a given load on the conveyer.

I claim:

25 1. Driving mechanism for a shaking conveyer, including a driving crank, driving means connected to the conveyer, a reversible spring drive unit swiveled on said driving means, and means for selectively detachably connecting either end 30 of said spring drive unit to said driving crank.

2. Driving mechanism for a shaking conveyer, including a reciprocable support secured to the conveyer, driving means connected to said support, a reversible spring drive unit swiveled on 35 said driving means, a driving crank, and means for selectively detachably connecting either end of said spring drive unit to said driving crank.

3. Conveyer driving construction including a driving crank, motion-transmitting means, a reciprocable support secured to the conveyer and connected to said motion-transmitting means, a spring drive unit reversibly mounted on said motion 40 transmitting means, and latch means selectively detachably connecting either end of said 45 spring drive unit to said driving crank.

4. Driving mechanism for a shaking conveyer, including driving means, a reciprocable support secured to the conveyer, means pivotally connecting said driving means to said support, a reversible spring drive unit swiveled intermediate 50 its ends on said driving means, a driving crank, and latch means selectively connecting either end of said unit to said driving crank.

5. A reversible spring drive for a shaking conveyer, including driving means adapted for connection to the conveyer, a spring drive unit swiveled intermediate its ends on the driving means for substantially horizontal swinging movement, and each end of said unit being adapted for detachable connection to a reciprocating driving member.

6. A reversible spring drive for a shaking conveyer, including driving means adapted for connection to the conveyer, a spring drive unit swiveled intermediate its ends on the driving means for substantially horizontal swinging movement, and latch means for selectively connecting either

end of said unit to a reciprocating driving member.

7. A reversible spring drive for a shaking conveyer, including driving means adapted for connection to the conveyer, a spring drive unit having a cross head swiveled on said driving means, a thrust member at each end of said unit, and springs interposed between the thrust members and said cross head, each thrust member being adapted for detachable connection to a reciprocating driving member.

8. Driving mechanism for a shaking conveyer, including a driving crank, a guide rod, driving means slidably mounted on said guide rod, means pivotally connecting said driving means to the conveyer, a spring drive unit swiveled intermediate its ends on said driving means, and means detachably and selectively connecting either end of said unit to said driving crank.

9. Driving mechanism for a shaking conveyer, including a reciprocable support secured to the conveyer, a driving crank, a guide rod secured at one end to said crank and slidably mounted at its other end on said reciprocable support, a driving sleeve slidably mounted on said guide rod and pivotally connected to said reciprocable support, a spring drive unit swiveled intermediate its ends on said sleeve, and latch means for selectively detachably connecting each end of said unit to said driving crank.

10. Conveyer driving construction including a driving member pivotally connected at one end to the conveyer for relative movement about a horizontal axis, guide means for said driving member, a reversible spring drive unit swiveled intermediate its ends on said driving member for swinging movement about a vertical axis, a driving crank, and a latch pivoted on said crank and adapted for detachable connection selectively with each end of said unit.

11. Driving mechanism for a shaking conveyer, including a driving member pivotally connected at one end to the conveyer, guide means for said driving member, a reversible spring drive unit having a cross head swiveled on said driving member, a thrust member at each end of said unit, springs of unequal strength interposed between said thrust members and said cross head, a driving crank, and latch means selectively connecting said driving crank with either of said thrust members.

12. Driving mechanism for a shaking conveyer, including a reciprocable support secured to the conveyer, a driving crank, a guide rod secured at one end to said crank and slidably mounted at its other end on said reciprocable support, a driving sleeve slidably mounted on said guide rod and pivotally connected to said reciprocable support, a spring drive unit having a cross head swiveled on said driving sleeve, a thrust member at each end of said unit, springs of unequal strength interposed between said thrust members and said cross head, and a latch pivotally mounted on said driving crank for selective detachable connection with either thrust member.

65

CHARLES N. BEBINGER.
